UNITED STATES PATENT OFFICE.

ELLA COLTON, OF OLEAN, NEW YORK.

DESIGN FOR A CLASP-FASTENER.

SPECIFICATION forming part of Design No. 24,998, dated December 24, 1895

Application filed October 3, 1895. Serial No. 564,553. Term of patent 7 years.

To all whom it may concern:

Be it known that I, ELLA COLTON, a citizen of the United States, residing at Olean, in the county of Cattaraugus and State of New York, 5 have invented and produced a new and original Design for Clasp-Fasteners, of which the following is a specification, reference being had to the accompanying drawing, showing the same.

10 The figure is a perspective view of my new and original design, showing a pair of heart-shaped leaves centrally related to each other at their larger extremities.

15 The leading feature of my design consists in a clasp-fastener the separate leaves of which are heart-shaped, as shown.

In the figure, A designates a leaf of the

clasp-fastener made substantially in the shape of a three-lobed heart in outline, with one of the lobes smaller than the other two. 20 Springing from this leaf is a second leaf B, upon the surface of which rises the supplemental heart-shaped piece C.

What I claim as my invention, and desire to secure by Letters Patent of the United 25 States, is—

The new and original design for a clasp-fastener as shown and described.

In testimony whereof I affix my signature in presence of two witnesses.

ELLA COLTON.
